CANE OR WALKING STICK

Louis Hage, San Jose, Calif.

Application November 27, 1933, Serial No. 699,908

10 Claims. (Cl. 135—47)

My invention relates to means for informing operators of motor driven vehicles that the pedestrian who shall display the stop sign in connection with this cane, when carrying same, demands the right of way for personal safety reasons.

This device will provide protection for any pedestrian who may use it, but particularly those who may have physical defects which endangers their safe passage through traffic lanes, such as impaired vision, hearing, mobility or mental confusion.

In particular, this invention will serve as a needed safety device for use of pedestrians in the crossing of traffic lanes which otherwise have not been provided with traffic control.

A further object of this invention is to provide a signaling device for the use of pedestrians so combined with a walking stick that a warning signal may be displayed or concealed at the will of the operator, even though he be a novice, and that when the signal is displayed it will be clearly visible to operators of motor vehicles to whom the signal is directed for a sufficient distance in which to bring a motor vehicle to a safe stop.

While my invention is particularly designed for the use of pedestrians, this device may be utilized for other purposes.

Referring to the drawing:

Figure 1 shows the appearance of the signalling traffic cane when used as a walking stick.

Figure 2 shows the appearance of the cane when held out in front of the operator and used as a signalling device.

Figure 3 shows a longitudinal section on line 3—3 of Figure 4.

Figure 4 shows a cross section on line 4—4 of Figure 3 when the stop signal is extended.

Figure 5 shows a cross section on line 4—4 of Figure 3 when the stop signal is concealed.

Figure 6 shows a cross section on line 6—6 of Figure 3.

Number 1 in the drawing represents the handle part of the cane, and 2 a hollow section in which are concealed the mechanical features necessary for the operation of the signal sign as well as the sign itself when not in use as a signal, this section also serving as the main body of the cane. At 3 is indicated the bottom end of the cane, and at 4 the cover over the slot in section 2 through which the sign screens pass when the signal is extended or retracted. At 5 is a trigger for releasing the signal screens to exposure.

In Figure 3 I show a compression spring 6 which forces trigger 5 into the stop slot in wheel

7. Wheel 7 is made fast to shaft 9a, and shaft 9a passes through bearing 8a into roller 10 and is made fast to said roller. Shaft 9b is hollow and has a bearing 11 fixedly inserted in its outer end. Shaft 9b passes through bearing 8b and then into roller 10 and is made fast to roller 10. Spiral rod 13 passes through bearing 11 at one end and is made fast to rod 15 at the other end.

Compression spring 12 is supported at one end on bearing 8b and at the other end on supporting washer 14. Washer 14 is made fast to rod 15. On rod 15 is a stop washer 16 which butts up against slide bearing 17 when the signal is exposed or extended. Bearing 17 is made fast to main body end 2 and has a passage that is square in cross-section to allow the square section of rod 15 to slide therethrough. At 18 is the bottom support for feather springs 20a and 20b, and at 19 is the top support for feather springs 20a and 20b, signal screens 21a and 21b and cover 4.

In Figure 4 the stop sign screens 21a and 21b are extended and supported by feather springs 20a and 20b, and show the position for signaling purposes.

In Figure 5 the stop or signal screens 21a and 21b are rolled over roller 10. The supporting feather springs 20a and 20b being folded down into the bottom supporting channel member 18, the top supporting member 19 with top cover 4 is pulled down so as to cover the screens and the openings through which they pass.

In Figure 6 I show a rod 15 which is square in cross-section, also a square bearing 17, so that when rod 15 is caused to move it can only slide but not turn. Rod 15 may be any shape in section other than round, with a similar fitting slide bearing so that the rod 15 may be made to slide but not turn.

The arrows shown in the cross-sections of roller 10 in Figures 4 and 5 show the direction the roller 10 turns in the opening and closing of the signal screens.

In practice, when the operator desires to signal he will pull the trigger 5 which in turn releases wheel 7. When wheel 7 is released compression spring 12 pushes rod 15 outwardly, and with rod 15 the spiral rod 13. The spiral rod 13 then causes roller 10 to turn through the action of sliding through bearing 11, thereby allowing the screens 21a and 21b to unwind from roller 10. When screens 21a and 21b unwind the feather springs 20a and 20b lift the top supporting bar 19 and cover 4 and also signal screens 21a and 21b. It will be seen that in all this action rod 55

15 can not turn but can only slide outwardly due to its cross-sectional configuration and a similar cross-section shape of the slide bearing 17.

In closing the signal screens the operator 5 pushes the end 3 on the ground or walk, thus causing rod 15 to be pushed inwardly, and with it spiral rod 13 which passes through bearing 11 which in turn causes roller 10 to turn and wind over it the screens 21a and 21b into space 10 22. This action will pull the signal screens inwardly and with them fold the feather springs, and bring the cover 4 inwardly over the screen openings.

When the closing operation is complete the 15 trigger 5 will have been pushed into the slot in the wheel 7 by compression spring 6 and so lock the closed members.

It will be understood that although I have herewith illustrated and shown but one specific 20 embodiment of my invention, changes in form, construction, and method of operation may be made within the scope of the appended claims without departing from the spirit of the invention.

25 I claim:

1. A cane having an extensible and retractable signal device mounted thereon, collapsible means constructed and arranged to support the signal in its extended position, means associated with the cane for collapsing the collapsible means and retracting the signal.

2. In combination, a hollow cane having an opening formed in the side thereof, signalling means disposed within the cane and extensible 35 through said opening, manually controlled means for extending the signal through the opening, and manually controlled means for retracting the signal into the cane.

3. In combination, a hollow cane having an 40 opening formed in the side thereof, a signal operative through said opening and normally disposed within the cane, trigger controlled means for projecting the signal through the opening, and means actuated by use of the cane to return 45 the signal through the opening to the interior of the cane.

4. In combination, a hollow cane having an 45 opening formed in the side thereof, a signal mounted within the cane and operative through 50 said opening, resilient means for urging the signal outwardly through the opening, means for retracting the signal against the outward urge of the resilient means, and releasable locking means for the signal when retracted.

5. In combination, a hollow cane having an 55 opening formed in the side thereof, a roller mounted in the cane opposite the opening, a signal device mounted on the roller and operative through the opening, resilient means for urging

the signal outwardly through the opening, cane actuated means for rotating the roller to retract the signal, and releasable locking means for the signal when retracted.

6. In combination, a hollow cane having an 5 opening in the side thereof, a roller journaled in the cane adjacent the opening, a flexible signal mounted on the roller and extensible through the opening, resilient means inserted between the signal and cane and adapted 10 to urge the signal into an extended position, a push-rod engaging the roller and extending through the end of the cane, resilient means for urging the rod outwardly through the end of the cane, push-rod actuated means for operating the 15 roller to retract the signal, and releasable means for locking the signal when retracted.

7. In combination, a hollow cane having an 20 opening formed in the side thereof, a signal operative through said opening and normally disposed within the cane, an operating rod mounted within the cane and extensible through the end remote from the handle thereof, resilient means for simultaneously urging the signal and rod into extended positions, means actuated by retraction 25 of the rod to simultaneously retract the signal, and releasable means for locking the signal and rod when retracted.

8. In combination, a hollow cane having an 30 opening in the side thereof, a roller journaled within the cane adjacent the opening, a signal mounted on the roller to operate through the opening, and actuating means for the roller comprising, a member slidably mounted in the cane and extending through the end remote from the handle, resilient means for urging the member 35 into an extended position while permitting its retraction when pressed against a resisting surface, driving means connecting the roller and member whereby movement of the member in opposite directions will rotate the roller in opposite directions, and releasable means for locking the member when retracted.

9. A cane having an extensible and retractable signal device mounted thereon, a collapsible 45 support associated with the cane to hold the signal in extended position and means associated with the cane and actuated by pressing the cane endways against a resisting surface while holding the cane by its handle end for collapsing 50 the support and retracting the signal.

10. A cane having an extensible and retractable signal device mounted thereon, means associated with the cane to effect the extension of the signal and support the same in an extended position, and means actuated by pressing the cane endways against a resisting surface while holding the cane by its handle end to retract the signal.
